UNITED STATES PATENT OFFICE

HORACE EDWIN HOBBS, OF LONDON, ENGLAND

DESIGN FOR A TAG

Application filed November 16, 1929. Serial No. 33,473. Term of patent 14 years.

To all whom it may concern:

Be it known that I, HORACE EDWIN HOBBS, a subject of the King of Great Britain, residing at 24-5 Fenchurch Street, London, E. C., England, have invented a new, original, and ornamental Design for a Tag, of which the following is a specification, reference being had to the accompanying drawing, forming part thereof.

Figure 1 is a front view and Figure 2 is a back view of a tag, showing my new design.

I claim:

The ornamental design for a tag, as shown.

HORACE EDWIN HOBBS.
